United States Patent Office

Des. 181,548
Patented Nov. 26, 1957

181,548

VAPORIZER OR SIMILAR ARTICLE

Robert J. Reading, Stratford, and William J. Cook, Trumbull, Conn., assignors to General Electric Company, a corporation of New York

Application January 7, 1957, Serial No. 44,424

Term of patent 7 years

(Cl. D83—1)

Fig. 1.

Fig. 2.

Fig. 3.

Figure 1 is a front perspective view of a vaporizer or similar article embodying our new design;

Figure 2 is a side elevational view thereof;

Figure 3 is a top plan view thereof;

Figure 4 is a front elevational view thereof; and

Figure 5 is a bottom plan view thereof.

It is to be understood that the ribbing in Fig. 1 is continuous around the circumference of the vaporizer as shown in Figs. 2, 3, and 4.

We claim:

The ornamental design for a vaporizer or similar article, substantially as shown and described.
